RAILWAY TRACK

Filed Dec. 19, 1928

UNITED STATES PATENT OFFICE

WILLIAM WHALEY, OF KNOXVILLE, TENNESSEE, ASSIGNOR TO MYERS-WHALEY COMPANY, OF KNOXVILLE, TENNESSEE, A CORPORATION OF TENNESSEE

RAILWAY TRACK

Application filed December 19, 1928. Serial No. 327,030.

This invention relates particularly to such railway tracks as are used in mines or quarries or other industrial work to bring loading machines or cutting machines or cars or other 5 track-mounted apparatus to the place at which such apparatus is to be used.

It is desirable to place the track-mounted apparatus for operation on or adjacent the line of the rail track and to also place said apparatus for wide lateral reach at either side of the line of said track.

For the purpose of bringing the working apparatus forward according to the forward advance of the position at which the work is 15 to be done, the rail track is to be extended forward, from time to time, as the work progresses.

For adapting the apparatus to work laterally from the line of the main track, it is desirable 20 to have the apparatus supporting trackage laterally from the line of the main track. For example, in a coal mine, it is desirable to so position a coal loading machine, supported on the track, into positions for a wide reach 25 in a room or entry, whereby the loading machine may load coal from a wide strip of floor space. Such wide reach is also desirable when coal cutting machines are supported on rail tracks, and when mine cars 30 are to be placed for loading coal or other mineral by hand, or when a track-mounted conveyor is to be placed near piles of material for movement by the aid of the conveyor.

In track-mounted loading machines, such 35 as the machine described in my Letters Patent of the United States No. 940,999, dated November 23, 1909, the gathering or loading end of the machine can reach sidewise from the middle line of the track only a certain distance, and can therefore load only from in front of the end of the track and to a certain distance from each side of the middle line of the track.

In such work it has heretofore been the custom 45 to lay a second track similar to a switch track, to allow the working apparatus to be brought laterally from the middle line of the main track. In other cases a considerable length of the track, including the forward section, has been shifted sidewise, so as to

bring the end section to or toward material which could not otherwise be conveniently reached. In other cases, a curved section of ordinary track has been inserted between straight track sections and secured to the abutting ends of the straight sections, the track section at the front of the curved section being thus turned sidewise.

The object of my invention is to provide a more simple and more convenient track structure adapted for lateral shifting at the forward end.

My improvement constitutes an attachment to the forward end of an ordinary rail track section, said attachment permitting sidewise movement of its forward part without disconnecting the attachment from the forward end of said regular or ordinary section.

In the accompanying drawings,

Fig. 1 illustrates a wide chamber or room in 70 a coal mine with an ordinary rail track on the middle longitudinal line of said room and my track extension attachment in position on the forward end of said regular or ordinary rail track;

Fig. 2 is a plan of the two sections which constitute my track extension attachment;

Fig. 3 is a side elevation of the structure shown by Fig. 2;

Fig. 4 is a detail, sectional side elevation of 80 the hinge joint by which the two sections of Fig. 2 and Fig. 3 are joined to each other;

Fig. 5 is a horizontal section on the line, 5—5, of Fig. 4;

Fig. 6 is an upright, transverse section on 85 the line, 6—6, of Fig. 4;

Fig. 7 is a transverse section on the line, 7—7, of Fig. 2, looking toward the left;

Fig. 8 is a detail elevation of the joint formed at the ends of a main track section;

Fig. 9 is a horizontal section on the line, 9—9, of Fig. 8.

Referring to the drawings, C is an ordinary or main rail track section comprising ties, C¹, and rails, C², supported by said ties. 95 Each rail is of ordinary form having a foot, C³, an upright web, C⁴, and a head, C⁵. At their ends these rails, C², are joined to adjoining ends of other rails by means of bolts, C⁶, and tying plates, C⁷. (Figs. 8 and 9.) 100

My improved attachment or track extension consists of a rear extension section, A, and forward extension section, B. The rear ends of the rails of the section, A, are attached to the forward ends of the rails, C², and the sections, A and B, are joined to each other as will be described further on.

The section, A, is shown as comprising two cross ties, A¹, and two rail pieces, A², resting on and immovably secured to the cross ties by means of spikes or bolts, in the usual manner, excepting that said rail pieces are not parallel to each other. The rear end of each of said rail pieces abuts against the forward end of one of the rails, C², of the section, C, and is joined to said rail by a tying plate, C⁷, bolts, C⁶, passing through the web, C⁴, of the rails, C², and the tying plate and passing through the web, A³, of the rail pieces, A², and through the same tying plate. (See Figs. 8 and 9.) This, it will be observed, is the ordinary manner of rail joint construction used in mine car tracks.

Because these rail pieces, A², are secured to the rails, C², in the manner described, it follows that the gage or spacing of the rear ends of said rail pieces, A², from each other is the same as the gage of the track, C. But the forward ends of the rail pieces, A², are farther apart than are the rear ends of said pieces.

In Fig. 2 of the drawings, the line, X, shows the gage at the rear end of the section, A, and the line, Y, shows the gage at the front of the section, A, that gage being also the gage of the track extension section, B, from end to end. The purpose of this enlargement of the track gage will be explained further on.

The forward end of each rail piece, A², has a part of the web, A³, cut away between the rail foot, A⁴, and the rail head, A⁵, to receive between the foot and the head the rear end of a forked hinge block, B⁷, as will be described further on.

The track section, B, has cross ties, B¹, on which rest track rails, B². Each such rail has a foot, B³, and a web, B⁴, and a head, B⁵. As above indicated, the rails are straight and parallel to each other, all parts of each rail being equi-distant from corresponding parts in the companion rail. The cross ties, B¹, are parallel to each other, and each cross tie is joined to the adjacent rail by means of a single rivet, B⁶, extending loosely through one of the flanges of the foot of the rail, all the rivets going through the same flange. By this means joints are formed similar to the joints in a parallel ruler or in a folding ladder composed of parallel side rails and transverse rungs having their ends hinged to the side rails.

Each forked hinge block, B⁷, has an arm, B⁸, lying against each side of the web, B⁴, of the adjacent rail, B², while the rear end of said block extends between the head, A⁵, and the foot, A⁴, of the adjacent rail, A², of the

short extension section, A. At each rail, A², a bolt, A⁶, extends downward through the head, A⁵, and the hinge block, B⁷, and the rail foot, A⁴. The hinge block is loose enough on said bolt to allow turning of the block on said bolt. The head of each bolt is counter-sunk in the head, A⁵, of the adjacent rail, A², to allow smooth-passing of wheels over that part of the track. (Figs. 4 and 6.) Bolts, B⁹, extend transversely through the arms, B⁸, and the web, B⁴, of the rails, B², said arms being thus secured to the rails the same as the ordinary tying plates, C⁸, are secured for making rail joints. The forward end of the foot of each rail piece, A², has its corners cut away, as shown in Fig. 5, to make room for the lateral turning of the adjacent rail, B², with the bolt, A⁶, as an axle.

From the foregoing it will be understood that when the extension section, B, is directed straight forward so that its rails, B², are parallel to and equi-distant from the middle, longitudinal line of the track sections, C and A, the distance between the rails, B², from end to end, will be the distance shown by the line, Y, at the rear end of the section, B, in Fig. 2.

It has already been explained that the rail pieces, A², diverge from their rear ends to their forward ends, this divergence enlarging the gage of that part of the track section from the rear toward the front.

But that wider gage is to be so limited as to allow the track wheels of the machine or car or other structure to rest on said rails. The extent of this increase of gage will depend upon the width of the tread of the track wheels. It is practical to make this increase of gage as much as one inch or two inches.

When the extension section, B, is turned sidewise on the joints formed by the bolts, A⁶, the rails, B², B², of that section automatically approach each other. That movement may be continued until the limit of such movement, for practical purposes, has been reached—when the rails, B² have approached each other to make the gage of that section as narrow as can be traversed by the car wheels, that being the gage at the rear ends of the rail pieces, A². It is to be understood that the rear ends of the rail pieces, A², are to be as near each other as the car wheels will permit.

To illustrate, let it be supposed that the rails, B², of the extension section, B, are each fifteen feet long and that the gage of the ordinary track section, C, is forty-four inches and that the distance between the rails at the line, Y, of Fig. 2 is forty-six inches, then the rails, B², can be swung approximately four feet to either side of the middle line of the main track section, C, and the rear extension section, A, before the extension, B, has closed to the normal gage of forty-four

5 inches—the gage of the main track section, C. The distance between the forward ends of the rail pieces, A², of the extension section, A, will remain two inches wider than the gage of the track section, C, and the reduced gage of the extension track section, B, attained by swinging or turning that section sidewise, as above described.

10 This extra width or gage at the meeting ends of the sections, A and B, is necessary to accommodate the wheels of the machine or car in changing direction on the track, that change taking place at the junction between the section, B, and the section, A. In 15 practice, I have found that the track wheels of a machine or car pass over the hinge formed between the sections, A and B, and conform their course to the angle of this track as easily as on the short curves usually 20 found in railway tracks in mines.

It can readily be understood that the swinging or sidewise turning extension section, B, can be made of any desired length within the limit for easy handling; and such extension can be made up of two or more sections. The longer said section is made, the farther will be the lateral reach of its forward end for a given angle of turning on the hinges formed by the hinge blocks, B⁷.

25 30 It is to be noted that the section, A, might be made longer than indicated. But that would make the equipment less convenient for handling and using.

I claim as my invention,

35 1. In a railway track, the combination of a forward track section comprising two parallel rails, cross ties pivoted to said rails, and means for hinging said rails to another track section, the rails of one section meeting the 40 rails of the other section.

2. In a railway track, the combination of a forward track section comprising two parallel rails, cross ties pivoted to said rails, and hinge blocks on said rails for hinging said 45 rails to another track section, the rails of one section meeting the rails of the other section.

3. In a railway track, the combination of a forward track section comprising two parallel rails, cross ties pivoted to said rails, a second track section located at the rear of the forward track section, and means for hinging the rear ends of the rails of the forward section to the forward part of the second section, the rails of one section meeting the rails 55 of the other section.

4. In a railway track, the combination of a forward track section comprising two parallel rails, cross ties pivoted to said rails, a second track section located at the rear of the forward track section and having its rails separated farther at the front than at the rear, and means for hinging the rails of the 60 forward section to the forward part of the sec-

ond section, the rails of one section meeting the rails of the other section.

5. In a railway track, the combination of a forward track section comprising two parallel rails, cross ties pivoted to said rails, a second track section located at the rear of the forward track section and adapted to have the forward ends of its rails meet the rear ends of the forward section, and means for hinging said meeting ends of the rails to each other. 70 75

6. In a railway track, the combination of a forward track section comprising two parallel rails, cross ties pivoted to said rails, a second track section located at the rear of the forward track section and adapted to have the forward ends of its rails meet the rear ends of the forward section, and hinge blocks and bolts for forming hinges at the meeting ends of said rails. 80 85

7. In a railway track, the combination with a main track section comprising rails and cross ties, of a second track section comprising rails adapted to be joined to the rails of the main track section, cross ties secured to said rails, a forward track section comprising two parallel rails and cross ties pivoted to said rails, and means for hinging the rear ends of said rails to the forward end of the second track section, the rear ends of the rails of the forward section meeting the forward ends of the rails of the second section. 90 95

8. In a railway track, the combination with a main track section comprising parallel rails and cross ties, a second track section comprising rails adapted to be joined to the rails of the main track section, cross ties secured to said rails, said rails being diverging from the rear ends to their forward ends whereby the forward ends are given a wider gage, a forward track section comprising two parallel rails and cross ties pivoted to said rails, and means for hinging the rear ends of said rails to the forward end of the second track section, the rails of the forward section meeting the forward ends of the rails of the second section. 100 105 110

9. In a railway track, the combination of a forward track section comprising two parallel rails, cross ties pivoted to said rails, a second track section having rails adapted to have their forward ends meet the rear ends of the forward section, a part of said rails having the web cut away and the other rails having hinged members adapted to enter the spaces formed by cutting said webs, and bolts extending through the rail heads and feet at said space and through said hinge members. 115 120

In testimony whereof I have signed my name, this twelfth day of December, in the 125 year one thousand nine hundred and twenty-eight.

WILLIAM WHALEY.
